UNITED STATES PATENT OFFICE.

WILLIAM D. HERSCHEL, OF PHILADELPHIA, PENNSYLVANIA, ASSIGNOR TO
JOSEPH O. COLLADAY, OF SAME PLACE.

SAW-ADJUSTING DEVICE.

SPECIFICATION forming part of Letters Patent No. 580,130, dated April 6, 1897.

Application filed September 3, 1896. Serial No. 604,704. (No model.)

To all whom it may concern:

Be it known that I, WILLIAM D. HERSCHEL, a citizen of the United States, residing in the city and county of Philadelphia, State of Pennsylvania, have invented a new and useful Improvement in Saw-Adjusting Devices, which improvement is fully set forth in the following specification and accompanying drawings.

10 My invention consists of a novel construction of a saw-adjusting device whereby the saw or other analogous device employed can be adjusted with great nicety and exactness relatively to the bed of the machine, the details of construction being hereinafter set forth, and specifically pointed out in the claims.

Figure 1 represents a plan view of a saw-adjusting device embodying my invention.

20 Fig. 2 represents a side elevation thereof. Fig. 3 represents a perspective view of a detached portion.

Similar letters of reference indicate corresponding parts in the several figures.

25 Referring to the drawings, A designates the bed of the machine, and B the uprights or standards therefor, the same being joined and braced by means of the upright web C.

30 D designates a bell-crank or elbow lever, which is pivoted at D' to the web C and is provided with the limbs E and F.

G designates a link which has one end pivotally attached to the limb F, while its other end is formed into a stirrup H, which is engaged by the screw of threaded stem J, which is attached to the hand-wheel L, which latter is swiveled in boxes K, fitted directly in the adjacent standard in any suitable manner, so that longitudinal movement of the stem J 35 is prevented when the same is rotated, whereby the link G is propelled either to the right or to the left by reason of the engagement of the threaded stem J with said stirrup.

M designates ways or recesses formed in the web C, in which the box N is adapted to play.

45 P designates a box in alinement with the box N, in which the shaft Q rotates, the latter carrying a saw Q' and being provided with the pulley R, to which the power may be applied.

S designates an apron or extension attached to said boxes N and P, whereby the same are caused to move in unison, said apron being carried by the limb E and having passed 55 through it the bolt T, on which is a tightening-nut, the latter being provided with the handle U for convenience of rotating the same. The portion of the bolt near its head occupies the segmental slot V in the side of the 60 web C and may be raised and lowered therein, whereby the position of the arm E relative to the bed A can be varied by rotating the hand-wheel L to the desired extent.

The limbs E of the lever D, the lower half 65 of the box N, the apron S, and the lower half of the box P are integral, and the web provides a single support for the several connected parts, excepting the screw J and wheel or crank L, thus providing a strong, durable, 70 and compact structure, there being a vast reduction in the members of the device.

The operation is as follows: When it is desired to adjust the saw relative to the table, it is only necessary to loosen the handle U 75 and to rotate the stem J in the direction desired, such rotation causing the link G to advance or retreat, thereby moving the boxes N and P, and consequently the shaft Q and the saw are raised or depressed thereby into 80 the desired position, and when the same has been reached by manipulating the handle U the parts can be locked, as is evident.

Having thus described my invention, what I claim as new, and desire to secure by Letters 85 Patent, is—

1. In a saw-adjusting device, a web, an elbow-lever mounted thereon, a box on said lever, an apron, a box thereon, means for raising and lowering said lever, and an arbor 90 mounted in said boxes with a pulley intermediate of the boxes, said lever, apron, and one-half of each box being integral, said web having therein a segmental slot which receives the adjacent box, the center of said slot being the axis of said lever.

2. A web provided with a recess in its upper edge, and a segmental slot in its side, an elbow-lever mounted on said web, a box on the upper limb of said lever occupying said 100 recess, an apron connected at one end with said box and extending laterally therefrom,

a box on the other end of said apron, an arbor mounted in said boxes, a bolt passing through said apron into said segmental slot, and a tightening-nut on said bolt in combination with the uprights B which support said web, the link G pivotally attached to said elbow-lever and provided with the stirrup H, the swiveled screw-stem J engaging said stir-

rup and the operating hand-wheel L, the swivel-boxes of said stem being mounted directly in the adjacent upright B.

WILLIAM D. HERSCHEL.
